BOBBIN CLUTCH

George H. Magrath, Whitinsville, Mass.

Application March 9, 1939, Serial No. 260,679

7 Claims. (Cl. 242—46.6)

This invention relates to bobbin clutches of the type having expansible clutching members which maintain the bobbin firmly in position during the spinning operation.

In bobbin clutches of the aforesaid type the lower ends of the clutching members are usually either mounted directly on the whirl or are supported so that they extend into a recess formed in the upper face of the whirl, and in either case their contacting surfaces usually extend through openings formed in a case which is secured to the blade independently of the whirl. Such constructions are subject to the objection that due to repeated doffing of the bobbin the whirl is apt to be driven down on the blade, thus separating it from the case with a consequent displacement of the clutching members which renders them inoperative. A further objection to such constructions is that when the clutching members are contracted by the bobbin there is produced about their free ends a gap in which lint collects, with the result that the operation of one or more of the clutching members is impaired. Consequently, the bobbin is not maintained properly centered and considerable damage may result, particularly when operating at high speeds.

The principal objects of the present invention are to provide a bobbin clutch which overcomes the aforementioned difficulties and to provide a bobbin clutch which is of simple design and of strong and durable construction, which is efficient and reliable in operation, and which can be manufactured at a relatively low cost.

Further objects relate to various features of construction, and will be apparent from a consideration of the following description and accompanying drawings, wherein:

Fig. 1 is an elevation, partly in section, of a bobbin clutch constructed in accordance with the present invention;

Fig. 2 is a longitudinal section through the bobbin clutch shown in Fig. 1;

Fig. 3 is a section on the line 3—3 of Fig. 1;

Fig. 4 is a top plan view of the outer casing;

Fig. 5 is an enlarged perspective view of the clutch spring;

Fig. 6 is a view similar to Fig. 2, but showing an inner case and clutch spring of modified construction;

Fig. 7 is a longitudinal section illustrating a further modification;

Figs. 8 and 9 are sections on the lines 8—8 and 9—9, respectively, of Fig. 7;

Figs. 10, 12 and 14 are longitudinal sections illustrating other modifications;

Figs. 11 and 13 are sections on the lines 11—11 and 13—13 of Figs. 10 and 12, respectively; and

Fig. 15 is an enlarged perspective view of the clutch spring of the embodiment shown in Fig. 14.

The embodiment shown in Figs. 1 to 5 comprises a blade 1 having a whirl 2 mounted thereon, the upper face of the whirl being formed with a recess 4 which receives the lower end of a bobbin clutch which comprises an outer case 5, an inner case 6, and a clutch spring 7, the entire clutch mechanism being supported independently of the whirl. The outer case 5 is formed with a head 10 having a press fit on the blade 1 and a plurality of circumferentially spaced fingers 11 depending from the head and defining a plurality of elongate slots or openings 12 (Fig. 3). The clutch spring 7 comprises a substantially flat body member 15 formed with a central opening to accommodate the blade 1 and a plurality of depending expansible spring fingers or segments 16 which accurately fit the slots 12, as shown in Figs. 1 and 3. The clutch spring 7 is held in position by the upper end of the inner case 6 which has a press fit on the blade 1, the lower end of the inner case being provided with a flange 18 which loosely fits within the recess 4 of the whirl 2, as shown in Fig. 1.

The flange 18 is formed with an annular recess 20 in which the lower ends of the case fingers 11 have a tight or pressed fit and in which the spring fingers 16 extend, their lower ends preferably terminating above the bottom of the recess, as shown in Fig. 2. The spring fingers 16 are of somewhat lighter or thinner stock than the case fingers 11 and are of course properly tempered and shaped so as to provide longitudinally and transversely convex surfaces, as illustrated in Figs. 2 and 3.

The construction and arrangement of parts are such that the spring fingers 16 are normally held against the outer wall of the recess 20 which constitutes a stop limiting their outward flexing movement, and when thus positioned their convex surfaces bulge or extend outwardly beyond the adjacent surfaces of the case fingers to an extent sufficient for them frictionally to hold a bobbin in place. Since the spring fingers 16 accurately fit the slots 12 and are held against the outer wall of the recess 20, all gaps and recesses are eliminated, thus minimizing if not

overcoming the danger of lint collecting about these parts.

When the bobbin B is applied about the blade, its base seats on the upper face of the whirl, as shown in Fig. 1, and the wall of its bore engages the spring fingers which are flexed inwardly about their upper ends, the inward movement being limited by the engagement of their lower ends with the inner wall of the recess 29. Although repeated doffing of the bobbin may result in driving the whirl downwardly on the blade, it will be noted that such displacement of the whirl does not interfere with the operation of the clutch mechanism.

The embodiments shown in Figs. 6 to 15 are, in principle, similar to and have the same mode of operation as the embodiment previously described, and the same or similar reference characters are applied to corresponding parts. In the embodiment shown in Fig. 6 the upper ends of the slots in the case 5^a are spaced from the head 10^a and the upper ends of the spring fingers 16^a are formed with shoulders or offsets 25 which accommodate the portions of the case immediately above the slots. The body member 15^a of the clutch spring is firmly held against the under surface of the head 10^a by the upper end of the inner case 6^a which is formed with a shoulder, as indicated at 26, so as to fit accurately against the shoulders 25 of the clutch spring.

In the embodiment shown in Figs. 7 to 9 the clutch spring 7 is supported by an inner case 6^b whose outer face is cut away or recessed, as indicated at 27 (Figs. 8 and 9), to permit a greater inward flexing movement of the spring fingers 16. Instead of providing the lower end of the inner case with an integral flange as in the previously described embodiment, I provide a ring 28 which has a press fit about the lower ends of the case fingers (not shown) and is effective to clamp them against the walls of the inner case lying between the recessed areas 27. The ring 28 and case fingers define recesses in which the lower ends of the spring fingers 16 are loosely received, it being understood that the outward flexing movement of the spring fingers is limited by the ring 28 which may occupy a recess formed in the upper face of the whirl, as illustrated in Fig. 1.

In the embodiment shown in Figs. 10 and 11 the case 5 and clutch spring 7 are substantially the same as in the embodiments shown in Figs. 1 to 6, but the inner case 6^c is recessed, as indicated at 32, between its ends so as to permit a greater inward flexing movement of the spring fingers than would otherwise be possible. In all other respects the construction and arrangement of parts are substantially identical to the embodiment shown in Figs. 1 to 6.

The embodiment shown in Figs. 12 and 13 comprises an outer case 5 and clutch spring 7 which may be of the type shown in Figs. 1 to 6, but in place of an inner case I provide a supporting member 35 which has a press fit on the blade 1 and is positioned so as to clamp the body 15 of the clutch spring against the under surface of the head 10 of the case. The lower end of the clutch mechanism is provided with a retaining member 36 circumscribed about and in relation to the blade 1 and formed with an annular recess 20. The lower ends of the case fingers 11 have a forced fit within the recess 20 and the free ends of the spring fingers 15 loosely fit therein as in the previously described embodiments, it

being noted that the walls of the recess constitute stops for limiting the inward and outward flexing movement of the spring fingers 16.

The embodiment shown in Figs. 14 and 15 is somewhat similar to that shown in Fig. 6, in that the outer case 5^d and the inner case 6^d are modified to accommodate a clutch spring 7^d formed with a cylindrical body portion 38 which is mounted on a neck 40 formed on the upper end of the inner case. The spring fingers 16 accurately fit the slots in the outer case and the lower ends of both the case fingers and the spring fingers are received in the recess 20 formed in the flange 18 at the lower end of the inner case, as in the previously described embodiments.

In each of the embodiments herein shown the clutch spring is firmly clamped in position against the head of the outer case, and as the spring fingers snugly fit between the fingers of the outer case, the clutch spring is securely anchored so as to withstand the shocks and stresses to which such parts are subjected. It will be further noted that in each of the embodiments the clutching mechanism and associated parts are supported independently of the whirl and, as previously pointed out, the clutch mechanism remains operative even through the whirl is displaced by repeated doffings of the bobbin. Moreover, the construction and arrangement of parts in each of the embodiments are such as to minimize if not to eliminate the accumulation of lint or other extraneous matter about the clutch members, and hence a more reliable operation and a lower maintenance cost is assured.

While I have shown and described different desirable embodiments of the invention, it is to be understood that the present disclosure is for the purpose of illustration and that various changes in shape, proportion, and arrangement of parts, as well as the substitution of equivalent elements for those herein shown and described, may be made without departing from the spirit and scope of the invention as set forth in the appended claims.

I claim:

1. A bobbin clutch comprising a blade, a whirl mounted on said blade, an outer case having a head fixed to said blade and a depending skirt formed with spaced openings, clutching means comprising a body member having depending expandable segments acting through said openings for frictionally holding a bobbin, and an inner case mounted on said blade independently of said whirl and fitting within said outer case, the upper end of said inner case clamping said body member against the head of said outer case.

2. A bobbin clutch comprising a blade, a whirl mounted on said blade, an outer case having a head fixed to said blade and a depending skirt formed with spaced openings, clutching means comprising a body member having depending expandable segments acting through said openings for frictionally holding a bobbin, and an inner case mounted on said blade independently of said whirl and fitting within said outer case, the upper end of said inner case clamping said body member against the head of said outer case, the lower end of said inner case having means for limiting the movement of said expandable segments.

3. A bobbin clutch comprising a blade, a whirl mounted on said blade, an outer case having a head fixed to said blade and a depending skirt formed with spaced openings, an inner case mounted on said blade and fitting within said outer case, clutching means comprising a body

member interposed between the head of the outer case and the upper end of the inner case, said body member having depending expandible segments acting through said openings for frictionally engaging a bobbin, and means carried by the lower end of said inner case for receiving the lower ends of said expandible segments to limit their movement.

4. A bobbin clutch comprising a blade, a whirl mounted on said blade, an outer case having a head fixed to said blade and a depending skirt formed with spaced openings, clutching means comprising a body member having depending expandible segments acting through said openings for frictionally holding a bobbin, an inner case mounted on said blade independently of said whirl and fitting within said outer case, the upper end of said inner case clamping said body member against the head of said outer case, and means circumsposed about said blade and supported independently of said whirl for limiting the movement of said segments.

5. Apparatus of the character described comprising a blade, a whirl mounted on the blade for supporting the lower end of a bobbin positioned about the blade, and clutching mechanism mounted on said blade above said whirl, but independent thereof, for frictionally holding the bobbin in position on said whirl, said clutching mechanism including a case fixed to said blade and having spaced openings in its periphery, clutching elements having parts acting through said opening and frictionally engaging the bobbin, supporting means secured to said blade for maintaining said clutching means in position, and means circumsposed about said blade for limiting the action of said clutching elements, said clutching mechanism constituting a unit structurally independent of said whirl so that axial movement of said whirl away from said clutching mechanism does not impair the operation of the latter.

6. Apparatus of the character described comprising a blade, a whirl mounted on the blade for supporting the lower end of a bobbin positioned about the blade, and clutching mechanism mounted on said blade above said whirl, but independent thereof, for frictionally holding the bobbin in position on said whirl, said clutching mechanism including a case fixed to said blade and having spaced openings in its periphery, depending clutching fingers acting through said openings for frictionally engaging the bobbin, means secured to said blade for maintaining said clutching elements in position, and means defining an annular recess for receiving the lower ends of said fingers, said clutching mechanism constituting a unit structurally independent of said whirl so that axial movement of said whirl away from said clutching mechanism does not impair the operation of the latter.

7. Apparatus of the character described comprising a blade, a whirl mounted on the blade for supporting the lower end of a bobbin positioned about the blade, and clutching mechanism mounted on said blade above said whirl, but independent thereof, for frictionally holding the bobbin in position on said whirl, said clutching mechanism including a case fixed to said blade and having spaced openings in its periphery, clutching elements having parts acting through said openings for frictionally holding a bobbin, and supporting means fixed to said blade for holding said clutching means in position, said supporting means having at its lower end a flange formed with an annular recess which receives the lower end of said case, said clutching mechanism constituting a unit structurally independent of said whirl so that axial movement of said whirl away from said clutching mechanism does not impair the operation of the latter.

GEORGE H. MAGRATH.
